Application March 18, 1938, Serial No. 196,588

14 Claims. (Cl. 34—18)

This invention relates to improvements in means and methods for drying out the shell or body of a barrel after the staves have been assembled, and prior to the charring of the barrel.

5 In the manufacture of barrels, particularly those for holding liquids, stave stock of proper length is arcuately cut to conform in cross section to the diametrical cross section of the barrel. Stave blanks so formed are tapered from the 10 middle toward both ends in such manner that when a barrel is formed therefrom it will have the desired end and mid-diameters and longitudinal curvature.

These staves, in proper number to form a barrel 15 shell, are assembled and the staves temporarily but solidly secured at one end by a heavy iron ring, with the opposite ends of the staves flaring apart, these flaring ends are then slightly drawn inward and a light ring placed thereon and the 20 shell is thoroughly steamed to permit subsequent bending of the staves. After steaming, the flared ends of the staves are drawn together and a second heavy ring placed thereon to solidly hold the staves together, and form the barrel shell. These 25 shells are then dried out and the rings driven down to tighten the staves. Subsequently the shell is charred, crozed, and further operations carried out to complete the barrel.

The present invention relates to a machine by 30 which the drying is accomplished, and to the method of accomplishing this drying as by the use of such a machine.

The objects of the invention are:

To provide means for drying barrel shells in a 35 continuous and uniform manner.

To provide, in connection with the drying means, means for conserving the drying heat and 40 steadyng the shells during drying, and means for displacing such conserving and steadyng means to release the shells successively for removal;

To provide means for ejecting the shells successively and automatically after their release; and,

45 To provide means for coordinating the action of the various instrumentalities used, and to improve the design and construction of the device as a whole, and of the details thereof.

50 The means by which the foregoing and other objects are accomplished and the method of their accomplishment will readily be understood from the following specification on reference to the accompanying drawings, in which:

55 Fig. 1 is a plan view of the machine with the

overhead walkway and other overhead construction largely omitted.

Fig. 2 is a corresponding front elevation with the barrels in place for drying.

Fig. 3 is a sectional elevation taken as on the 5 line III—III of Fig. 1.

Fig. 4 is an enlarged elevation of the ejector valve looking in the direction of the arrow IV in Fig. 3.

Fig. 5 is an enlarged section taken on the line 10 V—V of Fig. 3 looking in the opposite direction from that of Fig. 4.

Fig. 6 is an enlarged sectional elevation taken as on the line VI—VI of Fig. 1, and

Fig. 7 is a plan view taken as on the line VII— 15 VII of Fig. 6 with the barrel removed.

Fig. 8 is an enlarged plan view showing the ejector mechanism.

Referring now to the drawings in which the 20 various parts are indicated by numerals:

10 is the floor level of the room in which the device is placed, and 11, a pit below this floor level, this pit being shown in Fig. 1 as circular in plan with the exception that a portion 11—A is enlarged to receive certain mechanism. 12 is 25 the floor of this pit and 13 a rail disposed along a circular path to form a trackway concentric with the center post 14.

Disposed in the pit, is a carrier or turntable, which includes a hub 15 rotatably disposed around the post 14 and plates 16 integral with or secured to the hub as by welding. Disposed between the plates 16 and integrally secured thereto are radial arms 17, each of these arms preferably being made up of a pair of chan-

nel irons shown disposed with their flanges facing. Adjacent their outer ends the arms 17 rest on a pair of channel irons 18, 19, disposed with their webs facing and spaced apart to receive therebetween wheels 20. The wheels 20 are journaled as on pins 21 which extend through the webs of the channels and are secured against longitudinal displacement by keys or pins 22. Preferably the wheels 20 are provided with hubs

23, adapted to abut against the webs of the channels 18, 19. The channels 18, 19, preferably are curved each to form a continuous circular beam concentric with the post 14, and are secured to the under side of the beams 17 as by welding on in any usual or desired manner. The beams 50 27 preferably extend beyond the channels 18, 19, and are secured to peripheral struts 24 which may be straight between the beams 17. 25 are similar struts, spaced preferably at the same dis-

tance radially inward from the beam 18, that 55

the struts 24 are outward from the beam 19. 26 are floor plates, preferably of metal, which are secured on the beams 17 and the struts 24 and 25, to form a floor for the carrier.

5 30 are posts, preferably each made up of a pair of channel irons having their flanges facing, which posts each respectively rest on and extend upward from a beam 17 adjacent the inner edges of the floor plates 26, the posts preferably being integrally secured to the beams 17 as by welding.

10 31 are heaters or furnaces, each resting on a floor plate 26, each heater preferably having a heavy base 32 built of insulating refractory material, and an upper annular section 33, also of refractory material. The central opening 34 in the annular section is preferably of inverted frusto-conical form, with an inwardly projecting annular ledge 35 at the bottom. 36 is an opening extending radially inward from one side of the heater, this opening forming a combustion chamber lying along the top of the base 32. The outer end of this opening is closed by blocking 37 disposed around burners to be hereinafter mentioned.

15 40 are angle iron supports which are secured to the posts 30 as by welding, and which supports each extend from one post to the next. 41 are struts secured to the floor plates 26, as by welding, and extending upward therefrom. Each pair of these struts is capped by an angle iron 42 corresponding to the support 40 and integrally secured to the struts. 43 are barrel support bars, a pair of these bars resting on the supports 40 and 42 and being rigidly secured thereto. The bars 43 are slightly above the tops of the heaters 31 and are spaced apart somewhat more than the top diameter of the central opening 34 of the heater so that they are out of the direct line 40 of the heat arising therefrom. The top of the bars are a trifle higher than the floor level 10, so that barrels may be slid from the bars to the floor without catching on the floor edge.

45 44 are stop blocks each mounted on a bar 43. These blocks preferably each comprise a flat strap bent substantially into U shape, and disposed with the U legs upward, the bottom 45 of the U being conformed to encircle its bar 43. The two leg portions are spaced apart and are adapted 50 to be clamped together by a bolt 46, such clamping action also clamping the encircling portion 45 of the U on the bar 43. The stops are adjusted along the bars so that they will stop and center the barrel shells over the heaters.

55 50 are covers adapted to rest on the barrel 51 while it is being heated and to conserve the heat. Each of these covers preferably consists of a refractory material designated by the cover numeral 50 and a sheet metal backing 52. From 60 the sheet metal backing two pairs of rigidly secured U shaped loops 53 extend upward. Each pair of loops is disposed over an arm 54, which arm has a limited amount of movement between the backing 52 and the top of the loops 53, this 65 movement permitting the cover to adjustably seat and rest solidly on the top of the barrel when the arms 54 are lowered. The arms 54 are integrally secured to and extend substantially at right angles respectively from the tops of guide 70 rods 55; each rod is slideably mounted in a pair of brackets 56 extending laterally from the side of a post 30. The pair of arms 54 over each heater are connected together by a substantially A shaped cross member 55, the legs of the A being rigidly connected to the two arms 54. A

wheel 56 is journalled on a suitable bolt or pin 57 at the apex of the A member.

58 is a rail adapted to be engaged by the wheels 56. This rail in plan is curved to an arc concentric with the post 14, and lies in the path 10 of travel of the wheels 56. In elevation it has a central horizontal portion, an approach portion 59, and a run-off portion 60, the ends of both these latter portions dipping below the level of the horizontal portion, the approach end 59 being adapted to engage beneath each wheel 56 as such wheel moves into contact with it and to raise such wheel to the level of the horizontal portion. Such movement raises the A member 55, and raises the two arms 54 carried thereby 15 into engagement with the top of the loops 53, and continuing after such engagement, lifts the corresponding cover 50—A clear of the top of the barrel, holding the raised cover in such raised position until the wheels 56 pass off the run-off 20 end 60 of the track. 61 are a pair of beams supported by posts 62 lying outside the circle of the carrier and pit, from which beams hangers 63 depend into supporting engagement with the rail 58 and its approaches.

25 65 are a pair of beams supported at their opposite ends as by posts 66, 67, which posts rest on diametrically opposite portions of the floor 10, just outside the circle of the pit 11. 68 are boards forming a walkway along the top of the 30 beams 65. 69 are rungs of a ladder by which access may be had to the walkway 68 from the floor. 70 is a ladder supported by the beam 65 and depending therebelow adjacent the center of the pit. 71 is a hand rail.

35 72 is a chain belt encircling the beam 19. The chain 72 is driven by suitable gearing 73 from a motor 74, the motor preferably being at floor level and the gearing drive preferably including a vertically disposed shaft 75 leading from the 40 floor level down to the chain level in the pit.

40 Each of the heaters 31 is provided with two burners 80, adapted to heat a checkerwork 81 of refractory material which is disposed in the central opening 34 of the heater. The burners 80, 45 which are of well known construction, are supplied with fuel through pipes 84 each individually controlled by a cock 85. Fuel is supplied to these pipes from an annular header 86 through suitable connecting pipes 87 and 88 and a T 89, 50 the T also being connected to a usual form of pressure regulating mechanism 90.

55 The header 86 is supported on the beams 17 and moves with them as they turn. Fuel is supplied to the header 86 through a pipe 91 controlled by a cut-off valve 92. The pipe 91 extends inward and continues upward as a vertically disposed pipe 93 positioned in axial alignment with the center post 14. The vertical pipe 93 is rotatably connected and sealed through a sleeve 94 to a stationary pipe 95 which is also vertically disposed and in alignment with the pipe 93.

60 96 are supporting members carried by the beams 65 and which support the pipe 95. Pipe 95 is fed with fuel from any suitable source of supply, not shown.

65 100 is a second header which is also supported by the beams 17 and moves therewith. This 70 header is also connected to the rotatable vertical pipe 93 by suitable piping 101, provided with a cut-off valve 102. In addition to the burners 80, each heater is provided with a pilot light 103, these lights being fed through pipes 104 from the 75

header 100, and each of the pipes having an individual control cock 105.

The barrels after drying, are ejected automatically by an ejector having a head 110 adapted to engage the body of the barrel, this head being carried on the end of a piston rod 111, which rod extends through a stuffing box 112 into a double ended cylinder 113. 114 is the piston. In extended position the head 110 and rod 111 have considerable overhang. The stuffing box 112 is therefore made of extra length to provide, in connection with the piston, for carrying this overhang. The cylinder 113 is supplied with air through pipes 115, 116, the pipe 115 leading to the outer end of the cylinder and furnishing air to force the piston 114 inward and withdraw the ejector head 110, and the pipe 116 furnishing air to the inner end of the cylinder to force the plunger outward and eject the barrel from over the heater 33. The pipes 115, 116, lead from the cylinder 113 upward and overhead, preferably along the underside of the walkway beams 65, in this raised position being clear of rotating parts of the device. The pipes 115, 116, terminate at a control valve 117 which may be suitably supported as by a hanger 118 from the walkway beams 65 or other portion of the overhead structure. 119 is an air pipe leading from a suitable source of compressed air supply (not shown) to the control valve 117. The control valve is a typical form of four-way cock having a chamber 120 into which air is admitted through the pipe 119, and an oscillatable slide 121, shiftable by oscillation of a shaft 122. The slide 121, shown in section in Fig. 5, has an enclosed chamber 123, the top of which is cut away in this view, and is held in place by the air pressure in the chamber 120. 124 is an exhaust port open to the atmosphere. 125 and 126 are ports to which the pipes 115, 116, are respectively connected. The shaft 122 extends through to the outside of the casing and has a squared end 127 on which is secured a lever 128. The valve 117 is so positioned that as each barrel on the carrier in its turn reaches the point where it should be ejected, some one of the wheels 56 contacts the lever 128 and in its forward movement shifts that lever to the dotted position 128-A. When in the position 128 the slide chamber 123 is positioned over the ports 124 and 126, thus opening the inner end of the cylinder 114 through the pipe 116 to the atmosphere. Likewise the port 125 is in direct communication with the air entering through pipe 119, and through pipe 115 holds the ejector in retracted position. As the wheel 56 moves the lever 128 to the position 128-A, it shifts the slide chamber 123 to cover the ports 124 and 125, opening the outer end of the cylinder 114 through the pipe 115 to the atmosphere and supplying air to the inner end of the cylinder through the pipe 116. When the wheel 56 clears the lever 128 a spring 129 shifts the lever back to initial position.

In making use of the device, with all the control cocks 105 closed, fuel is turned into the header 100 by opening the pilot valve 102. The cocks 105 are then opened one at a time, and each pilot light in turn as it is supplied with fuel, is lighted. After all the pilot lights have been lighted, the cocks 105 are individually adjusted to provide an even pilot flame in each of the heaters. With all the control cocks 105 closed, fuel is turned into the header 86, by opening the main valve 92. Each of the cocks 85 may now be opened in turn and its burner ignited by the complementary pilot flame. With all the burners

ignited the pilot valve 102 is closed, simultaneously cutting off all the pilot lights, and each of the main burner cocks is adjusted to provide substantially identical flames from all the burners. Subsequent control of the burners is accomplished, as an entirety, by opening or closing the main valve 92. 5

In subsequent operation the pilot lights are turned on each evening by opening the pilot valve 102, and the main burners are then cut off by closing the main valve 92. During the night it is usually found advisable to maintain what may be termed an excessive pilot flame to keep the heaters partially warmed up. On starting up for operation each morning the main valve 92 10 is opened, the pilot lights igniting the burners, 15 after which the pilot valve 102 is closed.

In operation the burners, after ignition, are allowed to heat up the refractory checkerwork 81 until it is brought substantially to incandescence, 20 and the device is ready for barrel drying.

The motor is started and the carrier or turntable set in motion. As the covers 50 approach the rail 58, the inclined approach 59 engages each wheel 56 successively and raises the covers 25 to the positions 50-A.

As each heater reaches substantially the position 31-A (Fig. 2) near the center of the rail 58, a barrel shell 51-A (Fig. 8) is placed by hand on the support bars 43 and pushed back against the stops 44 which serve to position the shell both laterally and longitudinally of the bars. Shortly thereafter the run-off incline releases the cover 50 over this shell and the upper end is closed to conserve heat and steady the shell. During placing of the shell in position, the carrier and the heaters continue their movement, so that a second heater, as the heater 31-B, is moving into position to receive another shell. The loading operation is continued until substantially the entire carrier has been loaded. At this time, a shell which has been dried by the heaters nears the track approach 59 and as further movement continues the roller 56 climbs the approach raising the cover 50 to the position 50-A and releasing 45 the shell beneath such cover so that the shell may be ejected. During this cycle, the rollers 56 in succession contact the valve lever 128, and with each contact air is admitted first to the inner end of the cylinder 113 moving the ejector head outward, and then to the outer end retracting the head. This action is repeated as the first shell placed moves into alignment with the cylinder, and this shell is ejected automatically, furnishing space for an undried shell to be put on, 55 and permitting the cycle of operations to continue.

It will be obvious that the number of heaters on the carrier and the speed at which the carrier turns should be so regulated that the barrels will 60 be thoroughly dried between the time they are placed on the carrier and removed therefrom and, that these factors must be coordinated to the speed at which assembling and other operations are performed prior to drying, and finishing operations are carried out subsequent thereto. If it is found that the barrels are being under-dried the burner temperatures are increased by further opening the valve 92, or if over-dried the temperatures may be reduced by reducing such opening until proper treatment is accomplished. 65

It will be understood that many changes in detail may be made without departing from the spirit and intent of our invention and it is to be understood that we do not wish to limit ourselves 70 75

to such detail except as in any claim that may be set out.

We claim:

- 5 1. In a barrel drier, a horizontally disposed circular carrier, means for rotating said carrier, a plurality of heaters mounted on said carrier for movement therewith, a plurality of burners, at least one for each of said heaters, an annular header mounted on said carrier, and movable therewith, pipes from said header each leading to a said burner, each said pipe having a control valve, a vertically disposed supply pipe at the center of rotation of said carrier, a valve controlled, axially aligned pipe rotatably coupled and sealed to said supply pipe, and extending outward to said header; a plurality of means mounted on said carrier, each adapted to support a barrel-shell above a said heater, a like plurality of barrel-shell covers, each above a said heater, means each for engaging said covers, means for successively raising each said engaging means and cover to permit ejection and replacement of said barrel-shells, and means for lowering said engaging means and covers to permit said covers to rest on said barrel shells.
- 10 2. In a barrel drier, a rotatable carrier, means for turning said carrier, a plurality of heaters mounted on said carrier for movement therewith, a plurality of burners, at least one for each of said heaters, an annular header mounted on said carrier and movable therewith, pipes from said header each leading to a said burner, each said pipe having a control valve, a vertically disposed supply pipe at the center of rotation of said carrier, a valve controlled, axially aligned pipe rotatably coupled and sealed to said supply pipe, and extending outward to said header; and a plurality of means mounted on said carrier, each adapted to support a barrel-shell above a said heater.
- 15 3. In a barrel drier, a horizontally disposed rotatable carrier, means for rotating said carrier, a plurality of heaters mounted on said carrier for movement therewith, a plurality of burners at least one for each of said heaters, and means for supplying fuel to said burners; a plurality of means each mounted on said carrier and each adapted to support a barrel-shell above a said heater, a like plurality of barrel-shell covers, means each for loosely supporting a said cover above a said heater, means for successively raising each said support and cover, to permit removal and replacement of said barrel shells, and for lowering said supports and covers to permit said covers to rest on said barrel shells.
- 20 4. In a barrel drier, a horizontally supported carrier, means for advancing said carrier, a plurality of heaters mounted on said carrier for movement therewith, a plurality of means each mounted on said carrier and adapted to support a barrel-shell above a said heater, a like plurality of barrel-shell covers, each above a said heater, support means each for loosely engaging a said cover, means for successively raising each said support and cover, to permit removal and replacement of said barrel-shell, and for lowering said supports and covers to permit said covers each to be supported on a said barrel-shell.
- 25 5. In a barrel drier, a carrier, means for advancing said carrier, a plurality of heaters mounted on said carrier for movement therewith, a plurality of means each mounted on said carrier and each adapted to support a barrel-shell above a said heater, a like plurality of barrel-shell covers, each above a said heater, a plurality of

supports each loosely engaging a said cover, each said support having track engaging means, a track rigidly supported in the path of said track engaging means, said track having an inclined approach portion, a substantially horizontal center portion, and a run-off portion and being adapted to underrun said track engaging means, and respectively raise, support, and lower said supports and covers successively.

6. Means for drying barrels, including a working floor, a pit having a floor depressed below said working floor, a center post, a circular track concentric with said post carried by said pit floor, a carrier centered on said post, and having supporting wheels running on said track, means for turning said carrier, a plurality of heaters mounted on said carrier for movement therewith, the tops of said heaters being below said working floor, a plurality of means each adapted to support a barrel-shell above a said heater, the tops of said support-means being substantially at said working floor level, a like plurality of barrel-shell covers, each above a said heater, means for supporting a said cover, means for successively raising each said support and cover, and for lowering said support and cover to permit removal and replacement of barrel-shells, said lowering permitting said covers to rest on said barrel-shells.

7. Means for drying barrels, including a working floor, a pit having a floor depressed below said working floor, a circular track carried by said pit floor, a carrier having supporting wheels running on said track, means for turning said carrier, a plurality of heaters mounted on said carrier for movement therewith, the tops of said heaters being below said working floor, a plurality of means mounted on said carrier, each adapted to support a barrel-shell above a said heater, the tops of said support-means being substantially at said working floor level, a like plurality of barrel-shell covers, means each for supporting a said cover above a said heater, means engageable with said supports in succession, for raising and sustaining said supports and covers, to permit removal and replacement of barrel-shells and for lowering said supports to seat said covers on said replaced shells.

8. In a barrel drier a horizontally disposed circular carrier, means for rotating said carrier, a plurality of heaters mounted on said carrier for movement therewith, a plurality of burners at least one for each of said heaters, a plurality of pilot lights, one for each said heater, an annular header mounted on said carrier, and movable therewith, pipes from said header, each leading to a said burner, each said pipe having a control cock, a vertically disposed supply pipe at the center of rotation of said carrier, an axially aligned pipe, rotatably coupled and sealed to said supply pipe, a continuing pipe extending outward to said header, a cut-off valve on said continuing pipe, a second annular header mounted on said carrier, pipes from said second header each leading to a said pilot light, each said pipe having a control cock, a supply pipe leading from said rotatable pipe to said second header, a cut-off valve on said latter supply pipe; and a plurality of means mounted on said carrier, each adapted to support a barrel-shell above a said heater.

9. In a barrel drier a horizontally disposed circular carrier, means for rotating said carrier, a plurality of heaters mounted on said carrier for movement therewith, a plurality of barrel-shell supports, each above a said heater, a plurality of burners at least one for each of said heaters, a

plurality of pilot lights, one for each said heater, an annular header mounted on said carrier, and movable therewith, pipes from said header, each leading to a said burner, each said pipe having a 5 control cock, a vertically disposed supply pipe at the center of rotation of said carrier, a continuing axially aligned pipe, rotatably coupled and sealed to said supply pipe, and extending outward to said header, a cut-off valve on said continuing 10 pipe, a second annular header mounted on said carrier, pipes from said second header, each leading to a said pilot light, each said pipe having a control cock, a supply pipe leading from said continuing pipe inward from said cut-off valve to 15 said second header, and a cut-off valve on said latter supply pipe.

10. A barrel drier, including a horizontally disposed circular carrier, means for rotating said carrier, a plurality of heaters mounted on said 20 carrier for movement therewith, a plurality of support means mounted on said carrier, each adapted to receive and support a barrel-shell above a said heater for drying, a like plurality of barrel-shell covers, each above a said heater, 25 means each for engaging a said cover, means for successively raising each said engaging means and cover, to permit ejection and replenishment of said barrel-shells, means coordinated with said cover raising means for ejecting each of said 30 shells in succession, means for replacing each said ejected shell with an undried shell, and means for successively lowering said engaging means and covers to permit said covers each to rest on a said replaced shell.

35 11. A barrel drier, including a horizontally disposed circular carrier, means for rotating said carrier, a plurality of heaters mounted on said carrier for movement therewith, a plurality of support means mounted on said carrier, each 40 adapted to receive and support a barrel-shell above a said heater for drying, a like plurality of barrel-shell covers, each above a said heater, means each for engaging a said cover, means for successively raising each said engaging means and 45 cover, to permit ejection and replenishment of said barrel-shells, means coordinated with said cover raising means for ejecting each of said shells in succession, means for positioning an un-

dried shell in alignment over the ejection cleared heater, and means for successively lowering said engaging means and covers to permit said covers each to rest on a said positioned shell.

12. Means for drying barrels, including a working floor, a pit having a floor depressed below said working floor, a circular track carried by said pit floor, a carrier having supporting wheels running on said track, means for turning said carrier, a plurality of furnaces mounted on said 10 carrier for movement therewith, the tops of said furnaces being below said working floor, and a plurality of means mounted on said carrier each 15 adapted to support a barrel shell above a said furnace, the tops of said supporting means being substantially at said working floor level.

13. A barrel drier, including a carrier, means for progressing said carrier, a plurality of furnaces mounted on said carrier for movement therewith, a plurality of support means mounted 20 on said carrier, each adapted to receive and support a barrel shell above a said furnace for drying, and horizontally movable means positioned and operable to eject barrel shells successively from said supports at a predetermined point in 25 the cycle of operations, the tops of said supports being above the level of the tops of said furnaces whereby horizontal shift of said shells can be made.

14. A barrel drier, including a carrier, means 30 for progressing said carrier, a plurality of furnaces mounted on said carrier for movement therewith, a plurality of support means mounted on said carrier, each positioned and adapted to receive and support a barrel shell above a said 35 furnace for drying, the tops of said supports lying above the tops of said furnaces, horizontally movable means positioned to eject barrel shells successively from said supports at a predetermined point in the cycle of operations, means for operating 40 said ejection means, and means actuated by carrier movement for initiating said operations as such furnaces in succession align with said ejection means.
